HAMMOCK

Thomas A. Tischler, Detroit, Mich., assignor to
Joseph Sikora, Detroit, Mich.

Application July 21, 1936, Serial No. 91,719

5 Claims. (Cl. 5—129)

This invention relates to a portable hammock construction which can be disassembled and collapsed for easy carrying and handling by a single person or for storage in a comparatively small space but which is sturdy and firm when assembled.

A principal object is to provide a hammock frame which can be made largely of metallic tubing and which is bent in a manner to provide a resilient support for the hammock without disturbing its load-carrying ability.

There are two sets of tubes forming the frame each of which has the shape of a spread U and it is another object of the invention to so form the outer ends of each set that two hammock hooks will be jointly supported by both sets and will, in turn, firmly lock both sets together against relative end-wise movement. Removal of the hooks is readily done simply by lifting them from joint slots.

Another object is to provide an easily emplaced leg hook for connecting together adjacent branches of the spread U frame, preferably at points rather close to the outer ends thereof. No further bracing between the branches of the U is necessary to prevent further spreading of the tube sets away from each other and this completes the frame with a minimum of parts which are light in weight, comparatively inexpensive to manufacture, capable of being stored in a small space and capable of being set-up for occupancy in a brief period of time by one person.

Other objects and advantages will become hereinafter more fully apparent as reference is had to the accompanying drawing, wherein my invention is illustrated and in which

Figure 1 is a side elevation of my improved hammock frame,

Figure 2 is a plan view of the showing of Figure 1,

Figure 3 is an end elevation of the upper part of the frame with hammock attached, and

Fig. 4 is a longitudinal fragmentary section through the frame ends at the region of a tie bar.

More particularly 1 indicates each of two central tubular sections which are bent in such manner that they each form a spread U with a central portion 2 bent at its midportion. The outer branches 3 telescope into end sections 4, the bends 5 in the sections 1 constituting the stops to limit the length of telescoping. The outer ends 6 of the sections 4 are flattened and notched at 7 and the flattened ends are bent so that when two end sections are placed in contacting relation as best seen

in Figure 3, they will lie flat against each other with their notches 7 aligned.

In order to lock the end sections against relative longitudinal movement a hammock supporting member 8 similar in shape to the link of a chain, is placed in the aligned notches and strands 9 connect the members 8 with the bars 10 which are suitably secured to the hammock 11.

The connecting links 12, extending from one adjacent end section 4 to another, each have eyes 10 13 which extend through openings 14 in the sections 4 at points rather near the outer ends of these sections. Two of these links 12 are all that is necessary to prevent spreading of the frame during use. The eyes 13 are bent so that they 15 cannot be contained in a plane containing the axis of the bar portion. They are then each inserted through two openings in each end section 4 and then bent back into a common plane in 20 permanently locked engagement with their respective end sections. The two end sections which are thus locked together are relatively movable for collapsing against each other.

What I claim is:

1. A hammock frame comprising two main 25 frame members each of spread U formation and arranged in side by side relation, each of said members being flattened and notched at each end and having the flattened portion bent angularly with respect to the branches of the U, the flattened 30 portions of each of said members lying flat against the flattened portions of the other with their notches aligned whereby the midportions of said members are substantially spaced, and a hammock supporting means residing jointly in the 35 aligned notches at each end of said members to retain said members against relative endwise movements.

2. A hammock frame comprising two main 40 frame members each of spread U formation and arranged in side by side relation, each of said members being flattened and notched at each end and having the flattened portion bent angularly with respect to the branches of the U, the flattened 45 portions of each of said members lying flat against the flattened portions of the other with their notches aligned whereby the midportions of said members are substantially spaced, a hammock supporting means residing jointly in the aligned 50 notches at each end of said members to retain said members against relative endwise movements, and a link near each end of said members connecting the members to limit the amount of spreading thereof.

3. A hammock frame comprising two main 55

frame members each of spread U formation, each of said members consisting of a central portion and end sections telescoping therewith, each of said end sections being flattened and notched at its outer end, the flattened ends each being bent out of line with the remainder thereof, the flattened portions of one main member being in contact with the flattened portions of the other main member with their slots alined and hammock supporting means residing jointly in the alined slots.

4. A hammock frame comprising two main frame members each having the shape of a spread U, said members each comprising a central section curved in the middle and upturned ends, end sections telescopically fitting said ends and flattened and notched at their outer ends, said frame members being in side by side spread relation and having their flattened ends bent and 20 in contact at opposite ends of the frame with their

notches alined, hammock supporting means residing jointly in the alined notches at each end of the frame, and links having eyes at each end extending through holes in adjacent end sections to retain said frame members against undue spread-

5. A hammock frame assembly comprising two main frame members, said frame members each being in three sections with the mid-sections removable from the two end sections, each of said 10 end sections being permanently secured to an end section of the other main member and collapsible thereagainst, each of said end sections being flattened, bent and notched at its outer end, the outer ends of adjoined sections being lying 15 flat against each other with their notches alined, and hammock supporting means in the notches of adjoined end sections also serving as means to maintain said outer ends in contact during use.
